UNITED STATES PATENT OFFICE.

ALLEN B. NORTON, OF CLEVELAND, OHIO, ASSIGNOR TO ALUMINUM COMPANY OF AMERICA, OF PITTSBURGH, PENNSYLVANIA, A CORPORATION OF PENNSYLVANIA.

MULTIPART CORE.

Application filed February 23, 1924. Serial No. 694,480.

This invention relates to molds for cup-shaped articles and particularly to a sectional core for a piston mold.

One object of the invention is to construct a core composed of a plurality of rugged interlocking sections for a piston having an inwardly extending projection on its end wall. Another object is to construct a sectional core comprising a center section and side sections, the sections being aligned by longitudinal enlargements on the center section and corresponding recesses in the side sections co-operating therewith.

Another object is to construct a core composed of three sections of relatively the same cross sectional dimensions and weight for a cup-shaped casting having inwardly extending projections on the end and opposite side walls.

A further object is to construct a durable, rugged three part permanent core, for a piston having a boss on the inner side of the end wall and oppositely disposed wrist pin bosses carried by chordal webs.

Other objects will appear and be pointed out hereinafter.

In the drawings attached hereto and forming a part of this application:

Figure 1 is a fragmentary cross sectional view of a piston mold provided with my improved form of core.

Figure 2 is a side elevation of my improved form of core.

Figure 3 is a fragmentary cross sectional view similar to Fig. 1, but showing the core partly removed from the mold and casting.

Figure 4 is an inner end view of an assembled core embodying my invention, and

Figure 5 is a perspective view of a piston cast in a mold employing my core.

Although my invention relates generally to cup-shaped articles, it will be described hereinafter in connection with a piston mold of the type disclosed in the patent to Joseph H. Bamberg issued March 4th, 1919, Serial No. 1,296,588. Inasmuch as the present invention relates primarily to the construction of a core, only enough of the mold structure at present in extensive use and disclosed in the aforementioned Bamberg patent is shown herein to indicate to those skilled in the art

the cooperation of the mold with this improved form of core.

In the drawings, 1 indicates a mold base and 2 the mold halves which rest thereon and which have their meeting faces suitably shaped to form the outer walls of a casting cavity in which a piston 3 may be cast. Extending laterally through the sides of each mold halve 2 is a core pin 4 which projects sufficiently into the casting cavity to provide oppositely disposed hollow wrist pin bosses 5 on the casting 3. The end wall of the casting cavity is formed by the mold base 1. The mold halves 2 near their upper sides may carry bushings 6 to form at their lower ends a part or all of the end wall of the piston skirt, the inner surfaces of the bushings serving to hold the core sections in assembled relation when the mold halves are secured together. To facilitate ready escape of air and gases from the casting cavity as the metal is being fed into the casting cavity, numerous small air vents 7 are provided between the mold halves 2 and bushings 6, as well as between the bushings 6 and the adjacent core sections, the former recesses being shown greatly exaggerated and the latter recesses being not shown.

The piston casting 3 is provided with oppositely disposed wrist pin bosses 5 preferably cast hollow and in this instance carried by cross webs 8 which extend in substantially parallel relation across the piston at substantially right angles to a line joining the bosses. A rib 9 is provided across and integral with the head of the piston and extending downwardly therefrom to and being united integrally with the bosses. At approximately the center of the inner end wall of the piston, a centering boss 10 is provided for use in machining the piston. This boss 10 may assume various sizes and shapes, but as shown herein, it is substantially circular and of slightly greater cross sectional dimensions than the width of the rib 9 which adjoins. It will be noted that the wrist pin bosses 5, the rib 9 and the centering boss 10 are arranged in a plane substantially diametrically of the piston.

The core embodying my invention and adapted to the casting of a piston, such as is

shown in Fig. 5, is preferably split into a plurality of sections by substantially parallel planes arranged at right angles to a line joining the bosses, these planes being irregular 5 adjacent to the center of the core and forming enlargements on certain of the sections and recesses co-operating therewith on other sections. In the present embodiment of my invention, the core comprises a center or middle 10 section 11 and two oppositely disposed side sections 12. The center section 11 has on its opposite sides longitudinally extending raised portions or enlargements 13 and a centering boss recess 14 on its bottom. The ends of the 15 center section are curved and form, with the outer sides of the side sections, the inner side walls of the piston. Each side section 12 is provided on its inner surface with a longitudinally extending recess 15 adapted to co- 20 operate with the raised portion or enlargement 13 on the center section to align the side section therewith, and also contains on its outer surface an inwardly extending recess 16 in which the boss 5 and the boss carrying wall 8 25 may be cast. The assembled sections 11 and 12 have a rib recess 17 formed in the bottom thereof to form the rib 9 on the casting.

By referring to Fig. 4 it will be noted that the center section 11 is provided with a longitudinally extending raised portion or enlargement 13 which is greater in width than the cross sectional dimensions of the centering boss recess 17. Although these portions 13 may be variously shaped, a desirable configuration is shown in this figure, where the outer surface at right angles to the web recess 17 is substantially at right angles to this recess. With raised portions and co-operating recesses of the shape and size just described, it will be evident to those skilled in the art that the side sections 12 can be moved inwardly along the rib 9 until the recess 15 is above the centering boss 10 without, however, bringing sharp surfaces into contact with the still highly heated rib 9 and causing possible injury thereto.

The method of removing a core embodying my invention from a piston casting 5 is indicated in Fig. 3 of the drawings, where a center section 11 has been withdrawn longitudinally from the casting and between side sections 12, after which one side section 12 is moved inwardly until it clears the boss 5 and the boss carrying wall 8, after which it may be removed longitudinally from the casting. A similar procedure will remove the other section 12.

It will be noted that I have provided a sectional core for a piston having inwardly projecting bosses which is composed of a plurality of sections of substantially the same weight and thickness, while at the same time providing sections which are exceptionally rugged and capable of withstanding the hard usage to which such mold parts are subjected.

in ordinary use. Although the boss carrying walls 8 project inwardly of the piston to a considerable extent, I have been able to provide side sections 12 which have the requisite strength to resist the ordinary wear and tear 70 and tendency to warpage due to the temperature of the metal being cast, and at the same time have provided means for aligning the several sections when in assembled position. The aligning means, including the raised portions 13 and the co-operating recesses 15, also possess the further function of making possible the formation of a centering boss on the inner side of the end wall of the casting. It will be understood, of course, that the centering boss 10 may be cast either with or independently of the rib 9. 75 80

Having thus described my invention so that those skilled in the art may practice the same, what I desire to secure by Letters Patent is defined in what is claimed. It is to be understood, however, that various changes and alterations not amounting to invention may be made in the embodiment of my invention herein disclosed, without departing from the spirit and scope of my invention.

What is claimed is:

1. A sectional core, for a piston having an inwardly projecting centering boss on the end wall, which comprises a middle section having a centering boss recess in its end surface and raised portions on the sides thereof, the raised portions and centering boss being aligned diametrically of the core the said raised portions being larger than the boss recess and extending lengthwise of the said section, and side sections having interlocking engagement with the middle section and each having a wrist pin recess in its outer surface. 100 05

2. A sectional core, for a piston having an inwardly projecting centering boss on the end wall, which comprises a middle section and two side sections co-operating therewith, the said side sections each having a wrist pin boss recess in the outer surface and a recess lengthwise of the inner surface, the said central section having raised portions lengthwise of opposite sides co-operating with the said recesses on the inner surfaces of the side sections, and a centering boss recess on the inner end, the said middle section, the wrist pin boss recesses, the co-operating raised portions, recesses and centering boss recess being aligned diametrically of the piston. 105 110 115

3. A new and improved three part core, for a piston having an interior centering boss on the end wall, which comprises a middle section having a centering boss recess in the end surface and raised portions aligned with the said recess extending lengthwise of the opposite sides, and side sections each provided with recesses on its inner surface corresponding to the raised portions and wrist pin boss recesses on its outer surface. 120 122

4. A new and improved core, for a piston 130

having an interior centering boss on the end wall, which comprises three sections separated on lines substantially at right angles to a line joining the wrist pin bosses, the middle 5 section having a centering boss recess in the end surface and raised portions extending lengthwise of the side surfaces, the side sections having wrist pin boss recesses and recesses co-operating with the raised portion, all 10 the said recesses and raised portions being diametrically aligned with a line joining the boss recesses.

5. A new and improved piston core, having diametrically aligned wrist pin bosses and a 15 centering boss recess in the inner end thereof, the said core being split longitudinally into three parts on planes substantially at right angles to the diametrical line joining the said wrist pin boss recesses, the said planes 20 being irregular adjacent the said diametrical line and penetrating into the side sections an amount substantially greater than the diametrical dimensions of the said centering boss recess.

25 6. A core, for a piston, composed of three sections of roughly the same thicknesses, the middle section having a centering boss recess in its inner end, each side section having in its inner side a lengthwise groove of greater 30 cross sectional size than the said boss recess, and raised portions on the sides of the middle section interlocking with the grooves in the side sections.

7. A core, for a piston, comprising three 35 sections of roughly the same size, the middle section having a centering boss recess in its inner end, the said sections having interlocking tongues and grooves aligned with the boss recess and of greater cross sectional area than 40 half the corresponding area of the boss recess.

8. A sectional core having an end and sides 45 adjacent thereto shaped to form the interior of a hollow object comprising a center section having longitudinally extending enlargements at an intermediate portion of its sides and a plurality of side sections having longitudinally extending recesses cooperating with 50 said enlargements.

9. A three part core for forming the interior surfaces of a hollow object about its 55 end portion comprising a center section having longitudinally extending enlargements at an intermediate portion of the sides contacting the outer sections, the said outer sections having longitudinally extending recesses 60 forming to said projections.

10. A core, for a piston having oppositely 65 located wrist pin bosses, a rib extending across the inner side of the end wall of the piston 70 in diametrical alignment with the said bosses and a centering boss coinciding with and of greater diametrical and longitudinal dimensions than the said rib, which comprises a middle section having a centering boss recess 75 in its inner end, and longitudinal raised por-

tions of greater diameter than the centering boss recess along its opposite sides, and two side sections having their inner sides formed to cooperate with the said middle section, and their outer sides formed with wrist pin boss 80 recesses, the inner end of the assembled sections being formed with a diametrically extending rib recess.

11. A core, for a piston, composed of a middle and two side sections, each side section being formed with a wrist pin boss recess in its outer surface and the assembled sections being formed with a continuous rib recess 85 extending across the inner end in diametrical alignment with the said boss recesses, the middle section also being formed with a centering boss recess coinciding with but of greater depth than the rib recess, the co-operating side surfaces of the middle section and side sections being formed with interlocking raised portions and recesses respectively, of greater dimensions than the said centering boss recess.

12. A core, for a piston, composed of a middle and two side sections, each side section being formed with a wrist pin boss recess in its outer surface and the assembled sections being formed with a continuous rib recess 90 extending across the inner end in diametrical alignment with the said boss recesses, the middle section also being formed with a centering boss recess coinciding with but of greater depth than the rib recess, the co-operating side surfaces of the middle section and side sections being formed with longitudinally extending interlocking raised portions and recesses respectively of greater 95 dimensions than the said centering boss recess.

13. A core, for a piston, composed of a middle and two side sections, each side section being formed with a wrist pin boss recess in its outer surface and the assembled sections being formed with a continuous rib recess 100 extending across the inner end in diametrical alignment with the said boss recesses, the middle section also being formed with a centering boss recess coinciding with but of greater depth than the rib recess, the co-operating side surfaces of the middle section and side sections being formed with interlocking raised portions and recesses trapezoidal in 105 cross section respectively with one surface of the trapezoid extending at substantially right angles to the said rib recess the dimensions 110 of the said portions being greater than those of the said centering boss recess.

14. A three part core the end portion of which is adapted to form the interior surfaces of a hollow object cast thereabout comprising a center section and two side sections adjacent thereto, the center section being wider at its center than at its ends.

15. A three part core the end portion of which is adapted to form the interior surfaces 130

of a hollow object cast thereabout comprising a center section and two side sections conforming to the sides thereof, the sides of the center section being provided with longitudinally extending ribs intermediate the ends of the section.

16. A three part core the end portion of which is adapted to form the interior surfaces

of a hollow object cast thereabout comprising a cruciform center section and two side sections having longitudinally extending recesses to receive the transverse arms of the cross. 10

In testimony whereof I hereunto affix my signature this 18th day of February, 1924.

ALLEN B. NORTON.
